BOBBIN DRIVE

Alvis P. Rushton, Martinsville, Va., assignor to E. I. du Pont de Nemours and Company, Wilmington, Del., a corporation of Delaware

Application January 22, 1954, Serial No. 405,556

6 Claims. (Cl. 57—130)

This invention relates to driving of textile bobbins; it concerns especially means for transmitting rotational force to bobbins or the like.

In conventional textile winding equipment, force is transmitted to rotate the bobbin by means of metal lugs, tangs, pins, or other projections from the base of the spindle or top of the whorl. Often formed integrally with spindle or whorl, these projections are expensive to repair or replace when worn. Wear may be accentuated by imbalance or improper seating of the bobbin, with consequent increased vibration.

A primary object of the present invention is improvement in textile winding by comparatively vibration-free transmission of bobbin driving force. Another object is increase in the useful life of bobbin drive means. An object is provision of inexpensive easily replaceable drive means for bobbins. A specific object is manufacture of bobbin drive means from synthetic polymeric resins. Other objects of this invention will be apparent from the following description and the accompanying diagrams.

Figure 1 is an elevation (in section) of textile winding apparatus according to this invention. Figure 2 is a plan view of the apparatus of Figure 1. Figure 3 is a sectional elevation of the replaceable driving means taken on line 2—2 of Figure 2. Figure 4 is a plan view of another apparatus embodiment. Figure 5 is an elevation of the apparatus of Figure 4.

In general, the objects of this invention are accomplished by providing a resilient polymeric structure shaped to mate with a recess in spindle base or whorl and with a recess in bobbin base. This structure acts as a link between spindle and bobbin so that they rotate smoothly together. The link configuration is essentially a plurality of substantially radial tangs joined to one another by an arcuate portion that does not interfere with seating of the bobbin on the whorl.

Figure 1 shows in vertical cross section one form of drive link of this invention in place on textile winding equipment. Frame 1 supports spindle 2 by spindle bolster 3 journaled in bearings 4 and 4' and surrounded by spring 5. The body of whorl 6, which is pressed on the spindle, carries a groove for a drive belt (not shown). Slot 9 is formed transversely across the top of the whorl in line with the center, as appears more clearly in the plan view of Figure 2. A threaded extension 11 at the top of the whorl carries castellated waste spool 10.

Surrounding the spindle is drive link 15. The drive link may be considered to consist of tangs 16 carried on annular body 17. These tangs have substantially rectangular cross sections when viewed in the radial direction along arrow R and in the axial direction along arrow A. The lower part of the tangs fits into the slot in the whorl top. The upper part of the tangs extends above the whorl top to engage a recess in the bottom of the bobbin. Sleevelike extension 18 of the link body is designed small enough to fit inside the bore of the bobbin to center it about the spindle. The tangs may be extended at 19 to raise the body of the link out of

2

contact with the whorl so as to provide a grip or pry place for easy removal of the link from contact with spindle and whorl.

Shown separately is another drive link 25 (visible in Figures 4 and 5) whose annular body 27 circumscribes tangs 26, which are free at their inner ends. The body of this link is slightly elliptical, with the minor axis in line with the tangs. When squeezed along the major axis, transverse to the tangs, the tangs move slightly farther apart and the body rounds out to permit ready mounting of the link on the whorl, with the tangs extending inwardly and downwardly into the slot; release of the pressure seats the link firmly in contact with the whorl. As with the link shown in Figures 1, 2, and 3, the top part of the tangs extends above the slotted whorl top to engage a suitable recess in the bottom of the bobbin, which rests directly on the whorl top.

The drive links of this invention may be made from a synthetic polymeric resin having suitably high impact and shear strength, abrasion resistance, and resilience. Ease of formation into the desired shape, as by molding or machining, is highly desirable. Products of polycondensation reactions, such as polyesters or polyamides, are particularly suitable. Perhapse the most readily available material at this time is nylon, which proves eminently satisfactory on all counts. Nylon drive links have a useful life at least two times¹ that of conventional metal structures. Only the tangs, which contact both the driving and the driven elements (whorl and bobbin), need be made of the polymer, but it usually is most convenient to form the entire link of it.

Instead of only two radially extending tangs, the drive link may have three or more, usually symmetrically located about the center, extending either outward from an inner annular body or inward from an outer annular body, shaped analogously to those already described. The described features of a sleeve to bear in the bobbin bore or a slightly non-round configuration may be employed as desired. Of course, the tangs may be joined at both outer and inner extremities by a double body so that the resulting drive link resembles a spoked wheel. When a waste spool of the design shown is being used, the drive link should not extend beyond the whorl top to interfere with transfer of yarn to the waste spool or removal from it or with the winding of a transfer tail near the base of the bobbin.

An important advantage in addition to the tremendous reduction in wear afforded by the drive links of this invention, as compared with metal drive means for bobbins, is the vibration dampening provided by these drive links. Less vibration renders operation much quieter and more even, consequently improving the uniformity of the package being wound. A notable feature of the drive links of this invention is that they do not raise the bobbin off the whorl, which might displace or distort the winding pattern. Of course, the initial cost of these drive links is low, so replacement is quite inexpensive, as well as simply accomplished. The usual light color of the polymer enables an operator to observe readily whether a bobbin is seated properly. The polymer may be colored during manufacture to facilitate identification for different bobbins or materials being wound. Other advantages of practicing the present invention will come readily to mind.

What is claimed:

1. Bobbin drive link comprising a plurality of tangs extending substantially radially and axially from an annular body, said tangs being of substantially rectangular cross section in the axial direction.

2. The article of claim 1 made of nylon.

¹None of these nylon drive links has yet worn out.

3. Bobbin drive link comprising a cylindrical body and, extending axially and radially from the periphery thereof, a plurality of tangs of substantially rectangular cross sections in the radial and axial directions and in the direction perpendicular thereto.

4. The bobbin drive link of claim 3 wherein the tangs extend radially inward.

5. Apparatus comprising, in combination, a spindle-mounted whorl, a spindle-surrounding bobbin adapted to rest on the top of the whorl, both bobbin base and whorl top being recessed to receive a drive link, and a drive link having a plurality of radially extending tangs adapted to seat partly in the bobbin base and partly in the whorl top without raising the bobbin off the whorl and having an arcuate portion joining the tangs to hold them in 15 fixed relation one to another.

6. The drive link of claim 5 in which the tangs extend radially outward from the periphery of the body thereof.
